CLOTHES HANGER

Filed May 20, 1946

FIG. 4.

INVENTOR.

John P. Niskanen
BY Louis Hayke

ATTORNEY

UNITED STATES PATENT OFFICE

2,422,845

CLOTHES HANGER

John P. Niskanen, Detroit, Mich.

Application May 20, 1946, Serial No. 670,872

5 Claims. (Cl. 223—91)

1

My invention pertains to a clothes hanger which combines means for suspension of garments by clamping upon them, with means on which other garments may be imposed for support.

A further purpose is to provide a hanger in which the weight of the imposed garment or garments, will tend to secure a firmer grip on the clamped articles of apparel.

Another object of my improvement is to provide a garment hanger which is simple in construction, and which may be made economically, but which owing to its novel features, will be efficient and reliable.

I shall now describe my invention with reference to the accompanying drawings in which,

Fig. 1 is a side elevation of my hanger;

Fig. 2 is a top elevation of my said hanger;

Fig. 3 is an enlarged sectional view of my hanger, taken on line 3—3 of Fig. 1;

Fig. 4 is a side elevation of my hanger with parts thereof in a folded condition.

Similar numerals refer to similar parts throughout the several views.

In the main, my hanger includes what may be called a clamp suitable to be clamped upon such articles of apparel as trousers, skirts, etc., and foldable means adapted to support shoulder portions of garments such as coats. The clamp comprises two elongated flat members 10 and 11, disposed parallel to each other, one of said members, namely member 11 being in a hinged relation to the first named member 10. In order to effect the hinged relation, member 10 is provided with two posts 12, made of wire and extending upwardly from the narrow side thereof. At the top, each post turns in the direction of member 11, and then outwardly towards the respective end of member 10, parallel thereto, the parallel length of wire being marked 13.

Member 11 is provided with similar posts 14, correspondingly spaced from each other, and each ending in loop 15, coiled around said wire length 13 as it extends from post 12. The loops serve as hinges, making it possible to swing member 11 towards or away from member 10, the two members being opposite elements of the clamp as best shown in Fig. 3, wherein numeral 17 includes a garment clamped between said members. Both, posts 12 and posts 14, are provided with loose sleeves 16 acting as rollers. It will be noted that posts 12 and posts 14 are not disposed parallel to each other but are set at a slight diverging angle. The reason thereof will be explained presently.

2

I shall next describe the folding shoulder supports above referred to. Each of the supports comprises an elongated arm 18, made of a continuous length of wire, bent upon itself in the manner of a hair pin, each leg of the hair pin formation including a twist to produce an eye 19 and terminating in a prong 20. Each of the eyes embraces a transversely positioned shaft 21 which is held in place by an extension of post 12, said extension being looped around said shaft as indicated by numeral 22. A continuation of said extension forms a substantially arched span 23 leading to the other end of the clamp. At a point midway its ends, the span is equipped with a suspension hook 24.

The two prongs 20 of each arm serve as a forked lever so that the individual prongs bear from opposite sides against rollers 16 on posts 12 and 14, respectively, urging individual members 10 and 11 towards each other as best shown in Fig. 3.

The manner in which the hanger may be used, is as follows: Assuming that a garment such as a pair of trousers, is to be clamped between members 10 and 11, arm 18 is swung upwardly from its position shown in solid lines in Fig. 1, to a position shown in dotted lines and indicated by numeral 18a. As a result thereof, prongs 20, which normally bear from opposite sides against rollers 16, are disengaged therefrom, and members 10 and 11 are free to be spread apart for insertion of a garment between said members. Thereupon arm 18 fulcrumed at 21 is swung downwardly causing prongs 20 to engage from outside rollers 16 on posts 12 and 14, causing the members on which said posts are mounted to clamp upon the garment and to prevent the members from coming apart. As arms 18 extend outwardly in opposite directions they may suitably support such garments as coats, the weight of the garments so supported contributing to hold arms 18 in their downward position thus aiding prongs 20 to remain in place.

It will be obvious that some changes may be made in the structural design of my clothes hanger, without materially deviating from the inventive principles shown herein.

What I, therefore, wish to claim, is as follows:

1. A clothes hanger of the kind described including a clamp comprising two elongated flat members each disposed normally in a vertical plane and being in a hinged relation to each other, and a foldable arm at each end of the clamp, said arm being adapted to be swung down from a substantially vertical to a substantially

horizontal position, each arm including a forked lever to cause the members of the clamp to be forced towards each other, when said arm has been swung to its horizontal position.

2. A clothes hanger of the kind described including a clamp made up of two flat members each being normally disposed in a vertical plane and one being parallel to the other, two spaced wire posts rising from the narrow side of one of the members, two similarly spaced posts rising from the narrow side of the other member and hinged to the first named posts, an arm pivotally mounted at each end of the clamp and including a forked lever adapted to engage frictionally the posts on the respective members from two opposite sides to cause the members of the clamp to be forced towards each other longitudinally, and wire means to suspend said clothes hanger.

3. A clothes hanger of the kind described, including a clamp made up of two elongated flat members disposed parallel to each other, two wire posts rising from the narrow side of one of the members and similarly spaced posts rising from the other member and hinged to the posts first named, a pivoted arm at each end of the clamp in the plane thereof, the arm including a forked lever to engage the posts at the respective end of the clamp to cause the members of the clamp to

be forced towards each other, said arm being adapted to be swung upwardly to disengage the lever from the posts to spread the clamp members apart.

5. A clothes hanger including a clamp made of two elongated flat members longitudinally opposed and in hinged relation to each other, a pivoted arm at each end of the clamp and in the plane thereof, the arms extending in opposite directions, each arm including a forked lever responsive to the weight of garments on the arm to urge the opposed members of the clamp towards each other.

10 15 20 25 4. A hanger of the kind described including a trouser clamp composed of two elongated, flat members in a hinged relation and longitudinally opposed to each other, two arms extending from the clamp in opposite directions, one arm being pivotally mounted at each end of the clamp to swing down in the plane thereof from its inoperative and substantially vertical position to its operative and substantially horizontal position, each said arm including a lever to cause the members of the clamp to be forced towards each other when the arm has been swung downwardly to its operative position.

JOHN P. NISKANEN.
